UNITED STATES PATENT OFFICE.

WILLIAM N. MILLER, OF OAKLAND, CALIFORNIA.

IRONING BOARD.

Application filed October 6, 1923. Serial No. 666,875.

This invention relates to an ironing board and especially to improvements on the structure shown in my former patent, entitled "Folding ironing board," issued April 15, 5 1919, No. 1,300,993.

The object of the present invention is to provide a disappearing structure in the form of an ironing board or the like which is adapted to be built into an ordinary kitchen cabinet, cupboard or like piece of furniture; 10 a board which is adapted to be placed in the space usually employed for a drawer and to be concealed therein when not in use; a board which is pivotally secured in the 15 drawer space and which is adapted to be swung on a horizontal plane outwardly from said space when its use is required; a board which is adapted both to be extended and to fold, thus reducing the space required when 20 not in use; a board which is frictionally secured both against horizontal swinging movement and extending action; and further, a board which may be readily padded and covered for use.

25 One form which my invention may assume is exemplified in the following description and illustrated in the accompanying drawings, in which—

Fig. 1 is a perspective view of a cabinet, 30 the view being partly broken away to show the manner in which the ironing board is mounted.

Fig. 2 is a plan view of the cabinet showing the top removed, the view showing the 35 ironing board in folded and in concealed position within the cabinet and being pivotally secured on the right hand side of the cabinet.

Fig. 3 is a cross-section on line 3—3, 40 Fig. 2.

Fig. 4 is a similar cross-section showing the ironing board in extended position.

Fig. 5 is a detail side elevation of the ironing board looking at the opposite side of 45 Fig. 4.

Fig. 6 is a cross-section on line 6—6, Fig. 5.

Fig. 7 is a broken away perspective view showing the inner end of the beam and the 50 securing means employed.

The ironing board forming the subject-matter of the present application is a so-called disappearing type of board and may be built into a wall structure, a kitchen cabinet, a cupboard, or like piece of furniture. 55 It may also be applied to furniture already

in use, for instance, by utilizing a drawer space or the like. In the present instance the ironing board is shown as built into an ordinary kitchen cabinet, in which A indicates the front of the cabinet, 2 the sides, 3 the back, and 4 the top of the cabinet. Formed directly below the top portion is a space or chamber 5, and adapted to form a closure therefor is a door 6 hingedly secured 60 to the front of the cabinet as shown at 7; the door being adapted to swing downwardly when the ironing board is to be used and to be closed to conceal the ironing board when it is swung into the chamber or drawer 65 space 5.

The ironing board consists of a beam 8 of suitable length, which is pivotally secured to the bottom 9 of the drawer space by means of a bolt 10. The ironing board is supported by the beam 8 and it consists of two sections such as shown at 11 and 12. The main section of the ironing board, indicated at 11, is slidably mounted on the beam and it carries the front or auxiliary section 12. A 70 double hinge, consisting of three sections as shown at 13, 14 and 15, forms a connection between the ironing board sections 11 and 12, and thus permits folding of one section with relation to the other when the 75 ironing board is swung into the drawer space. The beam 8 has a length approximately equal to that of the drawer space, and it is adapted to be swung from the position shown in Fig. 2 to the position 80 shown in Fig. 1. The beam swings about the pivot 10 and it is adapted to be locked when extended by passing under a cam-shaped or inclined shoulder 16 formed in the back part of the cabinet previously referred 85 to by the numeral 3. It may furthermore be stated that it is frictionally held when in this position so that the board will not swing about its pivot 10 when being worked upon. This is accomplished as follows:

The inner end of the beam 8 is rounded as shown at 17 and one edge of the beam is slightly chamfered as shown at 18. When the beam is swung to extended position it passes in under an angle block 19 and a slot 105 20 cut in the back 3. The forward end of the slot is cam-shaped or angularly disposed as at 16, and as this portion engages the chamfered end of the beam indicated at 18, a frictional lock is obtained which secures the 110 beam against swinging movement about its pivot. The frictional interlock formed be-

5
tween the end of the beam and the rear section 3 of the cabinet is of further importance as it secures the inner end of the beam and holds it securely and snugly against the bottom section 9. This prevents tipping of the beam when the ironing board is being worked upon and as such forms a steady rest for the ironing board.

10
The main section of the ironing board indicated at 11 is slidably mounted on the beam 8 and may be moved substantially from end to end thereof, the board 11 being moved inwardly on the beam until it strikes the back 3 of the cabinet when it is desired 15
13 to swing the same into the drawer space; the auxiliary section 12 being first folded upon the main section 11 before the section is moved inwardly on the beam. The board 11 has a length substantially equal to the beam 8 but the auxiliary section 12 of the board is slightly shorter. The board therefore in reality consists of three main sections, the beam 8, the main board 11 and the auxiliary or folding board indicated at 20
25
30
12. These are positioned one on top of the other when the board is swung into the drawer space and as the ironing board sections thus positioned have a length slightly less than the beam 8, it is obvious that a fairly small drawer space may be employed.

35
A sliding connection between the beam 8 and the board section 11 is obtained by forming a tongue 19^a on each side of the beam. An opposed or interlocking tongue 20^a is secured to the board 11 on each side of the beam and a sliding connection is thus formed between the beam and the board 11. By referring to Fig. 4 it will be noted that the tongues 19^a and 20^a taper from end to end, the tongue 19^a having its smallest depth at the inner end as indicated at 21 and its greatest depth at the outer end as shown at 22. The tongues 20^a on the board 11 are reversed and a frictional lock is thus formed 40
45
50
between the board 11 and the beam 8 when the board 11 is moved to its extended position. This frictional lock is also of importance as it prevents longitudinal movement of the ironing board with relation to the beam when the board is being worked upon.

55
From the foregoing it can be seen that the ironing board is held against swinging movement when it is worked upon by means of the frictional interlock formed between the inner end of the beam 8 and the cam-shaped section 16 of the rear wall of the cabinet, and that longitudinal movement of the board is prevented by the frictional interlock formed between the opposed tongues 19^a and 20^a. The foldable section 12 of the ironing board is, as previously stated, hingedly secured to the main section 11 and it is supported when unfolded or extended by the tongue members 20^a as these 60
65
65
are extended forwardly of the main board

to which they are secured as indicated at 23. (See Figs. 2 and 4.) These extended ends form a support for the foldable section 12 and thus support the same when extended.

70
The double or offset hinge connection formed between the ironing board sections is of importance as it forms a spacing between the ironing board when folded; this being clearly illustrated by the dotted or folded position of the board section 12 shown at 12^a in Fig. 4. This spacing takes care of the padding and cover of the ironing board and therefore permits it to be quite heavily padded and it furthermore permits the board sections 11 and 12 to assume a 75
80
parallel position when folded. The double hinges are employed for the purpose of providing a space for the padding as already stated. It is for this reason that the hinge section 15 is secured to the board 12, as shown in Fig. 4, and it is also for the same reason that a depression 23^a is formed in the member 23; that is, the intermediate hinge section 14 swings about the two hinge sections 13 and 15. The board 12 swings 85
90
95
about the hinge section formed between the intermediate member 14 and the member 15 and as such swings in an arc. Such arcuate movement requires space and it is for this reason that the depression 23^a is provided.

100
In actual practice I have found that it is a very simple matter to pad and cover the board when extended as shown in Fig. 5, but that the padding and particularly the cover has a tendency to tear when the section 12 is folded. To prevent this tearing action, I employ a pair of rounded lugs such as shown at 24, and I also round the outer corners of the main board section 11 as shown at 25. By providing the rounded corners 105
110
115
25 and the rounded lugs 24, I find that the cover slides up and thus permits the board section 12 to be readily and easily folded without tearing the cover. It is therefore important that these features be employed.

120
125
130
To readily secure the cover when the padding has been put in place, a pair of canvas strips is employed in connection with the foldable section 12 as indicated at 27. These canvas strips are secured to the underside of the section 12 by means of a pair of wooden strips which are nailed to the board. The cover when put in place is folded in under the board and is there secured by passing pins through the cover and the canvas strips 27. It may thus be drawn tight and snugly over the board and wrinkles are entirely obviated.

To secure the cover to the main section of the board, a pair of side canvas strips is employed as shown at 29. These strips extend from end to end of the main section 11 and are secured by wooden strips 30 to the tongue sections 20.

The cover proper is stretched over the 130

main section of the board and it is then folded in under, pinned or otherwise secured to the canvas strips 29. The cover may thus be stretched tightly from end to end and 5 this taut position will be maintained as long as the board 12 is extended. The moment, however, it is desired to fold the board and to swing it back into the cabinet, it is readily accomplished as the rounded lugs 24 and 10 the corners 25 permit the unpinned section of the cover to slip up over the same and as such permits the section 12 to be folded or to assume the position shown at 12^a in Fig. 4. When the board has thus been folded it is 15 only necessary to push inwardly on the main section 11 until it strikes the rear wall 3 of the cabinet. The beam 8 is then grasped and swung about its pivot until it assumes the position shown in Fig. 2 and the front 20 door 6 may thus be swung up and closed, and the board is thus stored away and concealed.

In my previous patent referred to positive 25 stop lugs were employed for locking the beam when in extended position, and pins were employed for the purpose of securing the board when moved outwardly on the beam. These features complicated the construction and installation of the board and 30 did not satisfactorily serve the purpose intended; said features or objections have, however, been overcome by the present structure as friction locks are employed in each instance. The friction locks furthermore 35 simplify the construction and as such reduce the cost of manufacture and installation.

While the structure here illustrated represents an ironing board, it is obvious that it might be employed for a table, seat or other-

wise, and I therefore do not wish to limit 40 the application to the particular use here set forth. I also wish it understood that various changes in form and proportion may be resorted to within the scope of the appended claims, and that the materials and 45 finish of the several parts employed may be such as the experience and judgment of the manufacturer may dictate or various uses may demand.

Having thus described my invention, what 50 I claim and desire to secure by Letters Patent is—

1. The combination with a cabinet having a compartment formed therein, of a beam pivotally secured in the compartment and 55 adapted to be swung horizontally about a pivot into or out of the compartment, means engageable with one end of the beam for frictionally securing the beam against swinging movement when out of the compartment and an ironing board supported by the beam.

2. In a structure of the character described, a cabinet having a compartment formed therein, a beam pivotally secured in 65 the compartment and adapted to be swung about the pivot into and out of the compartment, an ironing board supported by the beam and means for securing the beam against swinging movement about its pivot 70 when swung out of the compartment, said means comprising a cam-shaped member on the inner end of the beam and a cooperating cam-shaped member in the rear wall of 75 the cabinet under which the inner end of the beam passes and by which it is frictionally secured.

WILLIAM N. MILLER.
